UNITED STATES PATENT OFFICE.

KARL SCHULTZ, OF BERWYN, ILLINOIS.

SKATE.

1,157,049.

Specification of Letters Patent. Patented Oct. 19, 1915.

Application filed May 10, 1915. Serial No. 27,245.

To all whom it may concern:

Be it known that I, KARL SCHULTZ, a subject of the Emperor of Germany, residing at 6431 Twenty-seventh Place, in the town of 5 Berwyn, county of Cook, and State of Illinois, have invented certain new and useful Improvements in Skates, of which the following is a specification.

My invention relates to improvements in 10 skates and particularly to skates of that class known as roller skates.

The objects of my invention are to provide a skate which is adjustable in length to enable it to be fitted to feet of different sizes, 15 to so construct the members thereof that they may be easily and quickly dismounted or assembled or adjusted relatively to each other to support the rollers yieldingly from the skate body, to arrange cushions of elastic material between the rollers and skate body that extend obliquely to the said body and at an angle to each other to properly 20 brace the parts thereof, and to connect the members of the body at a plurality of separated points. These and other objects I accomplish as hereinafter described and as particularly pointed out in the appended 25 claims reference being had to the accompanying drawings in which a preferred adaptation or embodiment of my invention is shown.

In the drawings: Figure 1, is a central longitudinal section through my improved skate on line 1—1 Fig. 2. Fig. 2, is a bottom plan view of my improved skate. Fig. 3, is a front end elevation of my improved 35 skate looking in the direction of the arrow X in Fig. 2. Fig. 4, is a detached fragmentary end view of the offset locking tongue, 40 of the toe member. Fig. 5, is an edge view of the fragment of the offset locking tongue shown in Fig. 4. Fig. 6, is a fragmentary detached view of the heel member to illustrate the longitudinal slotted construction 45 thereof.

In referring to the accompanying drawings in detail, like numerals indicate corresponding parts in the preferred adaptation

or embodiment of my invention shown therein.

My improved skate comprises two members, a toe member and a heel member and as these members differ from each other in many important particulars they will each be separately described.

The toe member has a substantially flat top plate 1, which is curved to conform generally to the shape of the forward portion of a shoe and is provided with a rearwardly extending portion 2 of narrower width 60 which terminates in a tongue 3, that is offset so as to extend in a plane slightly below but parallel with the plate 1, to which it is joined by a narrow oblique integral neck 4, formed as shown in Figs. 4 and 5.

An angular bracket 5 is suitably riveted or otherwise fastened to the undersurface of the plate 1, and the upper portions of its parallel sides are bent and separated sufficiently to provide a slideway for a purpose to be hereinafter explained. The cross or connecting portion or web of the bracket which extends between the two side portions thereof is arranged obliquely or at an angle to the top plate 1.

The bracket is provided with a depending lip 6, at each end which is provided with an opening or eye.

I prefer to employ but a single centrally located wheel 7, to support the front or toe member and to rotatably mount said wheel on a spindle 8, which extends between and is fastened to the lower extremities of an inverted U shaped support 9. This support 9 is provided with upwardly extending lips 10 85 which lap on the lips 6, and have corresponding openings through which a pivot pin 11 is fitted and screwed to pivotally connect the U shaped support to the bracket.

To cushion and limit the transverse oscillation of the support a block 12 of rubber or similar resilient material is fitted in place between the lips and the top and bottom portions respectively of the U shaped supports and the bracket as shown in Fig. 1.

It will be noted from Fig. 1, that the

bottom portion of the bracket and top portion of the support extend parallel with each other and at an angle with the top plate 1, and that the pivot pin 11, passes longitudinally through the block 12.

To additionally stiffen and strengthen the connection between the wheel supports and the top plate, a diagonal brace 13 extends from the rear extremity of the pivot pin 11, 10 upwardly and rearwardly to a connecting bolt 14.

A clamping device is attached to the toe member which consists of two jaws 15, and an adjusting screw bar 16.

15 The rear or heel member of the skate has a heel portion 17, which conforms substantially in shape to the heel of a shoe and a forwardly extending portion 19 of narrow width which has parallel sides and a central 20 longitudinal slot 20, which extends to and through the forward extremity of said portion 19, and is of even width throughout.

An angular bracket 21 substantially similar to the bracket 5 is fastened to the under 25 surface of the heel member and is provided with depending lips 22.

The rear wheel 23 is rotatably mounted on a spindle 24 which extends between and is fastened to the lower extremities of the 30 sides of a U shaped wheel support 25.

Two lips 26, extend upwardly from wheel support and lap and are pivoted to the lips 22 by a pivot pin 27.

35 A cushion block 28, is interposed between the bracket 21 and support 25 as shown in Fig. 1, which is formed of rubber or other suitable resilient material.

It will be observed by referring to Fig. 1, 40 that the blocks 12 and 28 are obliquely disposed with respect to the top plates of the toe and heel members and also extend at an angle to each other, one extending rearward and downward and the other forward and downward.

45 In fitting the top plates of the toe and heel members together the tongue 3 is slipped beneath the top plate of the heel member with the neck 4 extending obliquely through the slot 20, as shown in Fig. 1.

50 When the two members are adjusted relatively to each other to bring the skate to the desired length, the bolt 14 is tightened, thereby locking the two members against longitudinal movement.

55 The toe member is fastened to the heel member at its rear extremity by the offset tongue 3, which fits against and slides between the top plate of the heel member and also by the bolt 14 at or near its middle, 60 as shown in Fig. 1, thereby securing the two members to each other at widely separated points.

The top plates of the toe and heel members I prefer to construct of relatively light

and thin metal so that they may spring 65 slightly when the skate is fitted to the bottom of the shoe and thus accommodate themselves to the curve of the sole of the shoe. I also preferably provide the heel plate with a shallow longitudinal recess or 70 depression in which the extension of the toe plate fits and slides and to arrange a countersunk seat for the head of the fastening bolt 14, in the toe member.

75 While I have illustrated and described a preferred form of construction for carrying my invention into effect, this is capable of a wide range of variation, alteration, modification and change without departing 80 from the spirit of my invention. I, therefore, do not wish to be limited to the construction herein shown and described but desire to avail myself of all such variations, 85 alterations, modifications, and changes as fairly fall within the scope of the appended claims or may be construed to be within the scope thereof by invoking the doctrine of equivalents.

What I claim is:

1. A skate comprising a heel member having a forwardly extending longitudinally recessed portion and a central longitudinal slot in said forwardly extending portion, and a toe member having a rearwardly extending portion adapted to lap upon and slide in the longitudinal recess of the heel member, a tongue at its rear extremity adapted to fit against the undersurface of the heel member, and an oblique neck extending through the longitudinal slot of 100 the heel member and connecting the tongue to the rear extremity of the toe member.

2. A skate comprising a heel member having a forwardly extending longitudinally recessed portion and a central longitudinal slot in said forwardly extending portion, and a toe member having a rearwardly extending portion adapted to lap upon and slide in the longitudinal recess of the heel member, a tongue at its rear extremity 110 adapted to fit against the undersurface of the heel member, and an oblique neck extending through the longitudinal slot of the heel member and connecting the tongue to the rear extremity of the toe member; said 115 rearwardly extending portion, tongue and neck being integral.

3. A skate comprising a heel member having a forwardly extending longitudinally recessed portion and a central longitudinal slot in said forwardly extending portion, and a toe member having a rearwardly extending portion adapted to lap upon and slide in the longitudinal recess of the heel member, a tongue at its rear extremity 120 adapted to fit against the undersurface of the heel member, and an oblique neck extending through the longitudinal slot of the 125

heel member and connecting the tongue to the rear extremity of the toe member, a wheel support extending from the heel member, a wheel support extending from the 5 toe member, a brace extending diagonally from the wheel support attached to the toe member, and a bolt extending through the said brace, the slot of the heel member and the rearward extension of the toe member 10 for securing the said brace to the said mem-

bers and also fastening said members together.

In testimony whereof I have hereunto affixed my name in the presence of two witnesses.

KARL SCHULTZ.
